SEPARATOR

Curtis C. Baldwin, Ottawa, Kans.

Application April 8, 1933, Serial No. 665,159

1 Claim. (Cl. 209—136)

My invention relates to a separator and more particularly to a device to be used in connection with placer mining operations for separating sand from gold.

There are existent in some of our western states large areas of placer sand which are commercially unworkable by reason of the fact that they are situate far from an available supply of water. Placer mining is largely conducted in the vicinity of water in which water is used to wash the sand from the gold dust contained therein. Usually a hand operation known as "panning" is employed. An ordinarily diligent person working the whole day may "pan" as much as three dollars a day.

One object of my invention is to provide a device which will enable gold to be separated from placer sand without the use of water.

Another object of my invention is to provide a device which will effect a separation of sand from the gold in a novel and expeditious manner.

Another object of my invention is to provide a device which will perform the work of many men.

In the accompanying drawing which forms part of the instant specification and are to be read in conjunction therewith, and in which like reference numerals are used to indicate like parts in the various views;

Figure 1 is a diagrammatic sectional view of a device embodying one mode of carrying out my invention.

Figure 2 is a sectional view taken on the line 2—2 of Figure 1.

In general, my invention contemplates the provision of a plurality of inclined surfaces from which the placer sand is passed countercurrent to a stream of air. The velocity of the air stream is such that, assisted by the mechanical advantage of an inclined plane, particles lighter than gold will be blown out of the device, while particles heavier than sand, assisted by gravity, will move countercurrent to the direction of the air stream.

More particularly referring now to the drawing, a truncated cone 1 is made out of sheet metal or the like. It is placed in inverted position as shown in Figure 1 and terminates in a collecting trough 2. A second inverted truncated cone 3 is placed and supported in spaced relation to member 1 by means of supporting members 4. Another truncated cone 5 is built in spaced relation to truncated cone 3, as can be readily seen by reference to Figure 1. A member 6 is supported from standard 7 which houses

a shaft 8. Secured to the lower end of shaft 8 is a pulley 9 adapted to be connected to a prime mover. It is to be understood, of course, that any suitable means may be employed for rotating shaft 8. At the upper end of shaft 8 and attached thereto, I secure a distributing disk 10 adapted to be rotated by shaft 8. Distributing disk 10 carries a plurality of arms 11 to which are attached fan blades 12 of a sirocco fan. Between member 5 and member 11 provide a plurality of baffle plates 14. The air from the fan will leave at a tangent thereto. The purpose of the baffle plates is to deflect the air current so that the particles it acts upon will tend to move around the inclined planes in order that a measure of centrifugal force resulting from the circular motion will assist the air blast in effecting the separation.

In the device shown in Figure 1, a multi-stage separator is shown. Parts corresponding to those in the lower stage are numbered in the upper stage with like reference numerals, primed. The upper stage is supported by means of supporting members 15 which extend to the ground or platform upon which the separator is mounted. It will be observed that the upper stage is provided with a pair of hoppers 16 and 17, hopper 17 being supported from hopper 16 by spider 18. Secured to distributor plate 10 is a cylindrical member 19 which carries near its upper end the distributing disk 10'. Arms 11' are secured to the cylindrical member 19 in order that the fan blades 12' may be rotated.

In operation, material entering hopper 17 will fall through duct 20 and fall upon distributing plate 10. Centrifugal force will throw the material which, in the case of placer mining operations will be placer sand, outwardly against baffle 21. The sand passing down the inclined surface of member 5 will tend to stratify. As the sand passes lower edge 22 of surface 5, it will tend to fall vertically downwardly. The blast of air from fan 12 being directed by the baffles 14 will carry away the lighter dust. The heavier particles of sand, on reaching the inclined surface 3, will tend to move along the same in the direction imparted thereto by the air streams issuing between baffles 14. The velocity of air is such that the sand and material lighter than gold will gather speed as it moves around the surface 3. Centrifugal force will tend to widen the arc of travel of the particles until they reach the upper edge 23 of the surface 3, whence they pass out of the device. Gold and such particles as are not blown out of the machine in the

first stage are deflected by deflector 24 to the inclined surface 1 on which the operation is repeated.

- Material passing through the hopper 16 falls upon distributing plate 10' and is thrown outwardly and the operation described above is repeated. The member 1' of the upper stage terminates in an opening 24. If desired, a collecting pan may be placed under this opening.
- 10 In practice, however, this material will drop on surface 5 and the operation be continued. Before the placer sand is introduced into the machine, the classification may be by means of screens or the like. The material which passes through the screens, that is the more finely divided material, may be placed in the outer hopper, while the heavier material may be placed in the inner hopper 17. The heavy material may contain gold nuggets.
- 20 In practice, I have mixed gold dust consisting of particles of about twelve thousandths of an inch or more with gravel or sand particles having diameters of about two tenths of an inch or more. The device effected a perfect separation. The heavy material obtained from my machine will be the equivalent of a concentrated ore from which large amounts of gold may be readily recovered.

It will be observed that my device has many advantages. I am enabled to enter a placer deposit far from available water and handle large quantities of placer sand from which a concentrate consisting chiefly of heavy particles which contain much gold is recovered. This

concentrate may be then subjected to further processing. Frequently, gold nuggets the size of a BB shot are found. The concentrate contains considerable more gold than many men could pan in the same period of time.

5

It will be understood that certain features and subcombinations are of utility and may be employed without reference to other features and subcombinations. This is contemplated by and is within the scope of my claim. It is further 10 obvious that various changes may be made in details within the scope of my claim without departing from the spirit of my invention. It is, therefore, to be understood that my invention is not to be limited to the specific details shown 15 and described.

Having thus described my invention, what I claim is:

In a separating device a member having its inner surface generated along the surface of 20 an inverted cone, a second member having its exterior surface generated along the surface of an upright cone, means for supporting said second member within said first member concentric therewith and spaced therefrom with respective 25 bases of said members in overlapping relation, a centrifugal fan between said members and wholly within the projection of the base of said second member, a plurality of substantially vertical baffles inclined to the radii of said members 30 extending therebetween, and means for distributing material over the exterior surface of said second member.

CURTIS C. BALDWIN.
